[57] CLAIM

The ornamental design for a marine rescue and recreational board, as shown and described.

DESCRIPTION

FIG. 1 is a plan view of a marine rescue and recreational board embodying our new design showing the bow to the left;

FIG. 2 is a port side elevation view thereof;

FIG. 3 is a bottom view;

FIG. 4 is a bow end elevation view thereof;

FIG. 5 is a stern end elevation view thereof;

FIG. 6 is a plan view with the bow to the right of another embodiment of the marine rescue and recreational board;

FIG. 7 is a side elevation of the marine rescue and recreational board shown in FIG. 6;

FIG. 8 is a bottom view of the marine rescue and recreational board of FIG. 6;

FIG. 9 is a stern end elevation view; and

FIG. 10 is a bow end elevation view.
